UNITED STATES PATENT OFFICE

169,319

LAWN MOWER HANDLE

Herman C. Knarzer, Richmond, Ind., assignor to
Dille & McGuire Mfg. Co., Richmond, Ind., a
corporation of Indiana

Application February 8, 1951, Serial No. 14,142

Term of patent 14 years

(Cl. D40—1)

To all whom it may concern:

Be it known that I, Herman C. Knarzer, a citizen of the United States, residing at Richmond, in the county of Wayne and State of Indiana, have invented a new, original, and ornamental Design for a Lawn Mower Handle, of which the following is a specification, reference being had to the accompanying drawing forming a part thereof.

In the drawing:

Figure 1 is a front elevation; and

Figure 2 is a side elevation of a lawn mower handle, showing my new design.

I claim:

The ornamental design for a lawn mower handle, substantially as shown.

HERMAN C. KNARZER.
